United States Patent Office

Des. 184,882
Patented Apr. 14, 1959

184,882

GLOBE STAND

Carl H. Mapes, Evanston, and Richard M. Carrigan,
Skokie, Ill., assignors to Rand McNally & Company,
a corporation of Illinois

Application April 4, 1957, Serial No. 45,585

Term of patent 14 years

(Cl. D33—3)

Fig. 1 is an isometric view of the globe stand;
Fig. 2 is a reduced top plan view thereof;
Fig. 3 is a side elevation thereof;
Fig. 4 is a front elevation thereof; and
Fig. 5 is a bottom plan view thereof.

We claim:

The ornamental design for a globe stand, as shown.
